AUXILIARY HEAT RADIATOR FOR INTERNAL-COMBUSTION ENGINES

William A. Dennis, Los Angeles, Calif., assignor
of one-half to Harland F. Beardslee, Los Angeles, Calif.

Application August 5, 1948, Serial No. 42,574

2 Claims. (Cl. 123—41.1)

1

This invention relates to an auxiliary heat radiator for internal combustion engines.

Heretofore in the construction of automobile engines and also in the case of stationary internal combustion engines, it has been common practice to connect the outlet from the water jacket of the engine to the top of the radiator by means of rubber or composition hose. Such rubber or composition hose possesses the advantage of being flexible but has the disadvantage of being a poor conductor of heat. Consequently, water from the water jacket flowing toward the radiator, either through thermosiphon action or because of a water pump, has little opportunity to lose its heat until it reaches the radiator. As the water conducted from the water jacket to the radiator usually enters the radiator near its top, that water which is fed to the top of the radiator has an unduly and unnecessarily high temperature, placing a heavy burden on the radiator to cool it prior to its being returned to the water jacket. There are many situations wherein it is desirable to reduce the size of the radiator for a given internal combustion engine and in extremely warm climates it is desirable to maintain the water jacket temperature adequately low without increasing the radiator size.

An object of the present invention is to provide an auxiliary heat radiator consisting of a conduit formed of highly conductive metal which serves to connect the outlet from the water jacket of the engine to the top of the radiator. This conduit is characterized by the fact that on the exterior thereof it has a plurality of heat radiating fins arranged in planes other than perpendicular to the normal direction of air flow through the radiator and across the conduit. The flanged or finned conduit occupies or bridges the major portion of the space between the water jacket outlet and the radiator inlet and functions to radiate or conduct off to the surrounding atmosphere a substantial portion of the heat in the water flowing therethrough. Consequently, the water entering the top of the radiator has already been cooled substantially below the temperature that it had on passing out of the water jacket outlet. Some of the burden is taken off of the radiator permitting smaller sized radiators to be employed or, with a given size of radiator, more efficient cooling to be accomplished. Although the distance between the water jacket outlet and the top of the radiator may be relatively small, I find that with conventional automobile engines now on the

market, the drop in temperature obtainable on passing through the auxiliary radiator may be as much as 5° F.

By means of the improved construction it is not necessary to alter the radiator or the water jacket outlet in any respect and in the usual situation it is merely necessary to substitute the conduit embodying the present invention for the hose that conventionally connects the water jacket with the radiator. By employing flexible attaching means at the ends thereof, sufficient flexibility is obtained to satisfy all requirements heretofore met by rubber or composition hoses.

With the foregoing and other objects in view, which will be made manifest in the following detailed description and specifically pointed out in the appended claims, reference is had to the accompanying drawings for an illustrative embodiment of the invention, wherein:

20 Figure 1 is a view in side elevation of a portion of an internal combustion engine and its radiator illustrating one form of auxiliary heat radiator embodying the present invention as having been installed thereon;

25 Fig. 2 is a similar view but illustrating another form of construction that optionally may be employed;

Fig. 3 is a similar view illustrating still another form of construction that may be used; and

30 Fig. 4 is a vertical section taken substantially upon the line 4—4 upon Fig. 3.

Referring to the accompanying drawings wherein similar reference characters designate similar parts throughout, in Fig. 1 10 indicates an internal combustion engine which may be of any conventional or preferred type equipped with water jackets. 11 indicates its radiator which is connected at its lower end to the water jacket of the engine 10 by means of a short section of hose 12. The engine may or may not be equipped with a water pump for inducing a return of cool water from the bottom of the radiator 11 through the hose 12 to the water jacket of the engine 10. The outlet from the water jacket is indicated at 13 and the inlet to the radiator 11 adjacent the top thereof is indicated at 14. The inlet and outlet conventionally are connected by rubber hose or canvas hose coated with rubber or rubber-like material. However, 35 in accordance with the present invention I provide a connection consisting of a section of conduit 15 preferably formed of a good heat conducting metal such as, for example, aluminum. This conduit has a plurality of heat radiating flanges or fins 16 on the exterior thereof which

are preferably integral with the conduit and are arranged in planes other than perpendicular to the direction of normal air flow through the radiator 11. Thus if the engine 13 is regarded as an automobile engine, air flow through the radiator 11 may be assumed to be passing substantially horizontally therethrough from right to left and under these circumstances the fins 16 are arranged in planes at a decided angle thereto, as shown in Fig. 1, or approximately parallel thereto, as shown in Figs. 2 and 3. In the construction shown in Fig. 1, the planes of the fins are disposed at right angles to the axis of that portion of the conduit on which the fins are mounted. The ends of the conduit are suitably turned or directed so as to be disposed adjacent the outlet 13 and the inlet 14, respectively. An attaching means is provided for connecting one end of the conduit to the outlet 13 such as a short length of rubber hose or the equivalent indicated at 17 equipped with hose clamps 18 for attachment to the conduit 15 and outlet 13, respectively. In a similar manner the other end of the conduit is provided with a short length of hose 20 and hose clamps 21 to enable this section of hose to connect the conduit 15 to the inlet 14 of the radiator 11.

Water leaving the water jacket of the engine 13 flows upwardly through the conduit 15 to the top of the radiator 11 and as the conduit 15 and its integral fins 16 are formed of a good heat-conductor a substantial amount of heat present in the water may be radiated therefrom through the fins 16. The flow of air across the fins and across the exterior of the conduit is conducive to removing a substantial amount of the heat available in the water and as the rate of heat conduction increases with the difference in temperature between the water within the conduit and the surrounding air, it is manifest that the higher the difference between the temperature of the water and the temperature of the surrounding air, the greater the amount of heat that will be radiated through the radiator. Consequently the water on reaching the top of the radiator 11 will enter the radiator at a lower temperature than would otherwise be the case, relieving the radiator of some of its burden of cooling the water before it is returned to the water jacket.

In the preferred form of construction the conduit 15 bridges the major portion of the distance between the outlet 13 and the inlet 14, and the hoses 17 and 20 are made only long enough to form an adequate connection between the conduit and the outlet 13 and the inlet 14, respectively. These hoses, being flexible, will permit of whatever adjustment may be necessary if the radiator vibrates relatively to the engine 13.

In the construction shown in Fig. 2, the conduit 15a is the same as that previously described except that its radiating fins 16a, instead of being arranged at right angles to the axis of the conduit, are inclined relatively thereto so as to be substantially parallel to the normal direction of air flow through the radiator. By having the air sweep between and across the fins, a greater efficiency is accomplished in removing heat from the water conducted through the conduit.

In Fig. 3 the conduit 15b is substantially the same as that previously described but its fins 16b are radially arranged around the conduit so that they will all be substantially parallel to the direction of normal air flow adjacent the conduit.

From the above described construction it will be appreciated that, in installing the improved radiator on an automobile or stationary internal combustion engine, it is unnecessary to alter or modify either the engine or the radiator. The conduit is preferably cast to the desired shape, size and length and is connected at its ends to the outlet and inlet 13 and 14, respectively, by means of the short hose coupling sections. The improved auxiliary radiator may also be advantageously employed in cool climates as a heater in that it is merely necessary to surround the conduit with a suitable housing which will retain the heated air and conduct it to the interior of the automobile which it is desired to heat. I find that an auxiliary radiator of this character operates in a very efficient manner, cooling the water between the engine and the radiator substantially, thus enabling either a smaller radiator to be used or a conventionally sized radiator to function with maximum cooling efficiency under the most severe conditions.

Various changes may be made in the details of construction without departing from the spirit and scope of the invention as defined by the appended claims.

I claim:

1. In combination with an internal combustion engine having water jackets and a radiator, a heat-conducting conduit leading from the water jacket to the radiator having a plurality of external heat-radiating fins thereon, said fins being arranged in planes other than perpendicular to the direction of normal air flow through the radiator.

2. In combination with an internal combustion engine having water jackets and a radiator, a heat-conducting conduit leading from the water jacket to the radiator having a plurality of external heat-radiating fins thereon, said fins being arranged in planes other than perpendicular to the direction of normal air flow through the radiator, said conduit bridging the major portion of the distance between the internal combustion engine and the radiator.
